(57) **CLAIM**

The ornamental design for a brush handle, as shown and described.

DESCRIPTION

FIG. 1 is a top perspective view of my new design for a brush handle;

FIG. 2 is a bottom perspective view of FIG. 1;

FIG. 3 is a front view of FIG. 1;

FIG. 4 is a rear view of FIG. 1;

FIG. 5 is a right side view of FIG. 3;

FIG. 6 is a left side view of FIG. 3;

FIG. 7 is a top view of FIG. 3;

FIG. 8 is a bottom view of FIG. 3;

FIG. 9 is a top perspective view of a second embodiment of my new design for a brush handle;

FIG. 10 is a bottom perspective view of FIG. 9;

FIG. 11 is a front view of FIG. 9;

FIG. 12 is a rear view of FIG. 9;

FIG. 13 is a right side view of FIG. 11;

FIG. 14 is a left side view of FIG. 11;

FIG. 15 is a top view of FIG. 11; and,

FIG. 16 is a bottom view of FIG. 11.

The broken lines are included for the purpose of illustrating a portion of the handle that forms no part of the claimed design.
